UNITED STATES PATENT OFFICE.

EMILE LACOSTE, OF NEW ORLEANS, LOUISIANA.

VIOLIN ATTACHMENT.

1,353,763.

Specification of Letters Patent. Patented Sept. 21, 1920.

Application filed September 4, 1915. Serial No. 49,000.

To all whom it may concern:

Be it known that I, EMILE LACOSTE, a citizen of the Republic of France, residing at New Orleans, in the parish of Orleans and 5 State of Louisiana, have invented new and useful Improvements in Violin Attachments, of which the following is a specification.

This invention relates to certain novel and 10 useful improvements in stringed musical instruments and has particular application to an attachment for such instruments whereby the volume and duration of the tone are greatly increased.

15 In carrying out the present invention, it is my purpose to provide an attachment for stringed musical instruments which will embody a rod or bar and strings tuned to vibrate with strings of the instruments.

20 It is also my purpose to provide an attachment for stringed musical instruments, that when placed in its normal position in such an instrument, as for instance, a violin, will improve the tone of the instrument by 25 utilizing the full effect of the vibrations of the common strings producing a tone that is strong and penetrating, yet sweet, and when the attachment is displaced and moved so that its sound post is adjacent the bass bar, 30 will tend to render the tone clear, liquid and of improved quality and carrying power and also sweet, and again when moved in the opposite direction will produce strong ringing tones in combination with harmonious over- 35 tones.

With the above and other objects in view, the invention consists in the construction, combination and arrangement of parts hereinafter set forth in and falling within the 40 scope of the claims.

In the accompanying drawings;

Figure 1 is a longitudinal sectional view 45 through a musical instrument equipped with an attachment constructed in accordance with my present invention, the instrument being, in the present instance, a violin.

Fig. 2 is a transverse sectional view through the instrument and the attachment therein.

50 Fig. 3 is an end view of the tail end of the violin.

Fig. 4 is a perspective view of the attachment removed from the violin.

Fig. 5 is an enlarged cross sectional view through the attachment. 55

Fig. 6 is an enlarged fragmentary longitudinal sectional view through the same.

Similar numerals of reference designate corresponding parts in all of the views of the drawings. 60

I show my novel attachment in conjunction with a violin body 11. In accordance with my present invention the rear end wall of the body is formed centrally with an opening, while secured to the inner surface of the forward end wall of the body is a block 12, Fig. 1, having a recess 13 formed in the inner face thereof and in registration with the opening in the rear end wall of the body. 70

My novel attachment is preferably made up of a wooden rod 1, of rectangular form in cross-section and having recesses 8 in its four sides, tuning pins 2 and 3 on four sides of the rod adjacent to the rear end thereof, a band 4 constituting a string rest, a ferrule 5 having an offset flange 6 and also having apertures, Fig. 4, strings 7 arranged in longitudinal groups about the rod 1 and each connected at one end to one tuning pin, an end plate 9 carried at the rear end of the rod 1 and adapted to normally close the opening in the rear end wall of the body 11, and a knob or handle 10 on said plate 9. The forward ends of the strings 7 are carried through the said apertures in the ferrule 5 and are secured to the rod 1 in any appropriate manner which, *per se*, is not of the essence of my invention, and therefore is not illustrated. It will also be noted that the strings 7 rest on the band 4 and offset flange 6 and are stretched between the said elements and are arranged with their major portions opposite the recesses 8^a in the rod. 80

As shown in Fig. 1, the forward end of the ferrule 5 is removably arranged in the recess 13 of the block 12, and hence said block is enabled to support the forward end of the rod 1, the rear end of which is supported by the arrangement of the plate 9 between the rear end portions of opposite walls of the body. Manifestly when it is desired to tune the strings 7, the rod 1 may be drawn rearwardly through the opening in the rear end wall of the body 11 sufficiently far to afford ready access to the tun- 90 95 100 105

ing pins 2 and 3. At 8 the rod 1 is provided with a sound post. This sound post, however, will not interfere with the edgewise partial withdrawal of the rod 1 through the 5 opening of the body 11.

When the attachment is once tuned, it remains so for a relatively long period of time, as compared with the length of time 10 that the strings of the violin keep their tone, owing to the fact that the attachment is inclosed in the body of the violin and is therefore wholly protected against atmospheric changes.

While I have herein shown and described 15 one preferred form of my invention by way of illustration, I wish it to be understood that I do not limit or confine myself to the precise details of construction herein described and delineated, as modification and 20 variation may be made within the scope of the claims and without departing from the spirit of the invention.

Furthermore, I wish it to be understood 25 that although I have shown and described my device as used in connection with a violin, the same is equally applicable to stringed musical instruments of all types, such as violins, violas, cellos, guitars, etc.

I claim:

30 1. The combination with a stringed musical instrument body, said body having an opening in its rear end wall and also having interior supporting means in its forward end portion; of an attachment comprising a 35 rod extending through said opening in the rear end wall of the body and having its forward end portion disposed in said supporting means of the body, tuning pins on

the rear portions of the rod, strings connected at their rear ends to said pins and having their forward ends connected with the rod and also having their intermediate portions stretched between spaced supports on the rod, and means on the rear portion of the rod to close the opening in the rear end 45 wall of the body.

2. An attachment for violins comprising a rod having a plurality of sides and also having recesses in the intermediate portions of said sides, a ferrule secured on the forward end of the rod and having an offset flange and also having apertures, a band secured on the rear portion of the rod, tuning pins on the sides of the rod at points in rear of said band, a plate carried at the rear end 55 of the rod and having a handle, and strings connected with the rod and passed through the apertures in the ferrule and having their rear portions connected to the tuning pins.

3. The combination with the body of a 60 stringed musical instrument, said body having an opening in its rear end wall and interior supporting means in its forward portion, of an attachment adjustable endwise through said opening and removably arranged in said supporting means and having means to close the opening in the rear end wall of the body and also having strings and tuning pins on its rear portion to adjust the tension of said strings.

In testimony whereof I affix my signature in presence of two witnesses.

EMILE LACOSTE.
